(57) CLAIM

The ornamental design for a pacifier as shown and described.

DESCRIPTION

FIG. 1 is a top view of a pacifier showing my new design, the bottom view being a mirror image thereof;

FIG. 2 is a front view thereof;

FIG. 3 is a rear perspective view thereof;

FIG. 4 is a second rear perspective view thereof;

FIG. 5 is a right side view thereof, the left side view being a mirror image thereof; and,

FIG. 6 is a rear view thereof.

The broken lines depict portions of the pacifier that form no part of the claimed design.
